US0D1083519S

(12) **United States Design Patent** (10) **Patent No.:** **US D1,083,519 S**
(45) **Date of Patent:** **** Jul. 15, 2025**

(54) **CONTAINER WITH LID AND BASE**

(71) Applicant: **Starbucks Corporation**, Seattle, WA (US)

(72) Inventors: **Brandon M. Roberts**, Snohomish, WA (US); **Jonathan Levey**, Geneseo, NY (US); **Ryan M. Gorham**, Kirkland, WA (US)

(73) Assignee: **Starbucks Corporation**, Seattle, WA (US)

(**) Term: **15 Years**

(21) Appl. No.: **29/843,876**

(22) Filed: **Jun. 24, 2022**

(51) **LOC (15) Cl.** **07-09**

(52) **U.S. Cl.**

USPC **D7/602**

(58) **Field of Classification Search**

CLAIM

The ornamental design for a container with lid and base, as shown and described herein.

DESCRIPTION

FIG. 1 is a top perspective view of a container with lid and base showing an embodiment of our design;

FIG. 2 is a bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

1 Claim, 8 Drawing Sheets
